His Attorney.

UNITED STATES PATENT OFFICE

CHRISTIAN KRÄMER, OF BERLIN-PANKOW, GERMANY, ASSIGNOR TO GENERAL ELECTRIC COMPANY, A CORPORATION OF NEW YORK

MERCURY-ARC RECTIFIER

Application filed March 16, 1928, Serial No. 262,279, and in Germany July 23, 1927.

My invention relates to electric discharge devices and more particularly to large mercury-arc rectifiers of the type used for transmitting current between alternating and direct current power systems. The principal object of this invention is to provide an improved arrangement of the rectifier and its auxiliary apparatus.

The mercury-arc rectifiers used for power purposes commonly consist of an evacuated metal tank, or container into which the electrodes are sealed, supported on a steel framework. To take care of leakage through the seals and also gases that are generated during operation of the rectifier, each rectifier is equipped with an evacuating equipment consisting of a condensation vacuum pump, an intermediate vacuum chamber and a second vacuum pump. These pumps and chamber, as hitherto arranged, occupy considerable floor space and leave the space underneath the rectifier, unoccupied. In accordance with my invention the intermediate vacuum chamber is constructed as one or more of the supports for the rectifier, the second vacuum pump is mounted underneath the rectifier and the whole assembly is mounted on a portable base.

My invention will be better understood from the following description when considered in connection with the accompanying drawings, and its scope will be pointed out in the appended claims.

Referring to the drawing, Fig. 1, is a diagrammatic view of a conventional mercury-arc rectifier with its vacuum pumps, valves and the intermediate vacuum chamber. Fig. 2 is a front view of a rectifier embodying my invention.

Fig. 1 indicates a container 10 supported on a framework 11. A condensation vacuum pump 12 is connected to the container 10 through pipe 13 in which valve 14 and vacuum indicator 15 may be connected. The condensation vacuum pump is supported from the container 10 and is preferably of the type disclosed in Letters Patent of Irving Langmuir, No. 1,393,550. This pump discharges into an intermediate vacuum chamber 16 through a one way valve 17 which is so

constructed that it prevents gases reentering the container 10 in case the condensation pump fails. Another vacuum pump 18 often referred to as the "roughing pump" evacuates chamber 16, through pipe 19 and valve 20. In practice it is found that after the first complete evacuation of the container, pump 18 may be operated intermittently, that is, pump 12 discharges so small an amount of gases into the chamber 16 that considerable time elapses before the pressure therein is high enough to warrant operation of pump 18.

Fig. 2 shows container 10 supported on columns 20 which are hollow and are used as the intermediate vacuum chambers. They are connected to pump 18 and to each other through pipe 21 and valves 22. The condensation pump 12 is mounted on the side of container 10 and is connected through valve 24 to the container and through trap 27, pipe 24 and valve 23 to chamber 20. Another pipe 25 is shown connected to trap 27. This pipe branches off and leads to sealing chambers of the electrodes 26 and 28. This type of seal is disclosed in my Letters Patent No. 1,643,216.

The columns 20 may be of any suitable number and convenient size, one or more of which may be used as preliminary vacuum chambers, depending upon the volume required. These chambers and pump 18 may then be mounted on a base 29 and rollers 30 thus making a compact portable rectifier unit.

What I claim as new and desire to secure by Letters Patent of the United States is:

1. An electric discharge device comprising an evacuated container and electrodes sealed therein, a hollow support for said container, a plurality of vacuum pumps adapted to evacuate said container, said support being arranged to form a chamber connected between said pumps.

2. A mercury-arc rectifier, a plurality of vacuum pumps adapted to evacuate said rectifier, and a rectifier support arranged to form a vacuum chamber connected between said pumps.

3. In combination a mercury-arc rectifier, supporting members therefor comprising

chambers, a plurality of vacuum pumps, one of said pumps being mounted on said rectifier and operatively connected between said rectifier and said chambers, a second vacuum pump located underneath said rectifier and operatively connected to said chambers, and a portable base upon which said chambers and said second vacuum pump are mounted.

In witness whereof, I have hereunto set
10 my hand this 24th day of February, 1928.

CHRISTIAN KRÄMER.
